UNITED STATES PATENT OFFICE.

WILLIAM W. VOGEL, OF CHICAGO, OHIO.

SPANNER-WRENCH.

No. 872,484.

Specification of Letters Patent.

[Patented Dec. 3, 1907.

Application filed August 21, 1907. Serial No. 389,523.

To all whom it may concern:

Be it known that I, WILLIAM W. VOGEL, a citizen of the United States, residing at Chicago, in the county of Huron and State 5 of Ohio, have invented a new and useful Spanner-Wrench, of which the following is a specification.

This invention has relation to spanner wrenches especially adapted to be used for 10 screwing and unscrewing fruit jar caps and consists in the novel construction and arrangement of parts as hereinafter shown and described.

The object of the invention is to provide 15 a simple and an effective wrench of the character indicated which may be easily and readily applied to and detached from the jar cap and which may be operated upon the same without crushing or mutilating the cap.

20 It consists primarily of a pair of jaws lying in the same plane and which are adapted to move longitudinally with relation to each other in order to accommodate jar caps of different diameter. A cuneate 25 handle bar is arranged to move transversely across the jaws and in its transverse movement moves the said jaws longitudinally with relation to each other.

In the accompanying drawing:—Figure 1 30 is a perspective view of the wrench applied to a jar cap. Fig. 2 is a transverse sectional view of the jar cap showing the wrench jaws in elevation with parts in section, and Fig. 3 is a sectional view of the jar cap and 35 wrench, the section through the wrench being cut longitudinally of the handle bar thereof.

The wrench consists of the jaws 1 and 2 40 which lie in the same plane and each of which is provided with a flange 3. The flanges 3, 3 are oppositely disposed with relation to each other. The inner end of the jaw 2 is bifurcated as at 4 and is provided at each side of said bifurcation with a loop 45 5. The inner end of the jaw 1 is provided with a loop 6 which lies within the bifurcation 4 of the jaw 2. The cuneate handle bar 7 passes transversely through the loops 5, 5 and 6. Said handle bar is provided at

its larger end with a perforation 8, whereby, 50 the wrench may be hung upon a nail or other support, and the said handle bar 7 is provided at its reduced end with a punched up section 9 which is disposed to one side of the handle bar 7 and presents an obstruction 55 which prevents the handle bar 7 from becoming disengaged from the loops of the jaws.

From the foregoing description it is obvious that, when the handle bar 7 is moved 60 longitudinally so that the reduced end thereof is brought between the loops 5 and 6 of the jaws, the said jaws 1 and 2 may be spread apart so that the flanges 3, 3 may receive the opposite side of a jar cap between 65 them. The said handle bar 7 is then moved longitudinally in the opposite direction so that the inclined edges of the said handle bar, operating against the sides of the loops 5 and 6 will draw the jaws 1 and 2 together 70 and cause the oppositely disposed flanges 3, 3 to positively engage the sides of the jar cap. Thus the implement is applied to the cap; then, by turning, the wrench, using the handle bar 7 as a lever, the jar cap is turned 75 axially and is screwed or unscrewed upon the jar. To disengage the wrench from the jar cap the parts are moved in a reverse manner to that above described.

Having described my invention what I 80 claim as new and desire to secure by Letters-Patent is:—

A wrench comprising jaws adapted to move longitudinally with relation to each other, one of the jaws having at its inner end 85 a bifurcation with loops located at the opposite sides thereof, the other jaw having a loop at its inner end which lies within the bifurcation of the first said jaw, and a handle bar located slidably in said loops. 90

In testimony that I claim the foregoing as my own, I have hereto affixed my signature in the presence of two witnesses.

WILLIAM W. VOGEL.
